UNITED STATES PATENT OFFICE.

OTTO GRAUL, OF LUDWIGSHAFEN-ON-THE-RHINE, GERMANY, ASSIGNOR TO BADISCHE ANILIN & SODA FABRIK, OF LUDWIGSHAFEN-ON-THE-RHINE, GERMANY, A CORPORATION.

PROCESS OF PRODUCING 2-CHLOR-ISOPENTANE.

1,202,282.

Specification of Letters Patent.

Patented Oct. 24, 1916.

No Drawing.

Application filed March 13, 1913. Serial No. 754,146.

To all whom it may concern:

Be it known that I, OTTO GRAUL, citizen of the German Empire, residing at Ludwigshafen-on-the-Rhine, Germany, have invented new and useful Improvements in Processes of Producing 2-Chlor-Isopentane, of which the following is a specification.

This invention consists of a process by which an excellent yield of 2-chlor-isopentane and thereby of isoprene can be obtained from a mixture of petrol hydrocarbons, which consists chiefly of normal pentane and isopentane, each of the isomeric pentanes being converted into 2-chlor-isopentane.

According to this invention the hydrocarbon mixture is first treated with chlorin, so that, for the greater part, monochlorin derivatives are produced, and then these monochlorin derivatives are separated by distillation from more highly chlorinated products and from unaltered hydrocarbons. In this way a mixture is obtained which consists practically of five different monochlorpentanes, namely—

and possibly also contains small quantities of the isomer

Should any tetramethyl-methane be present in the initial material, this gives rise in the first place to monochlor-pentane of the formula—

and this, upon distillation, is converted into 2-chlor-isopentane (formula I). The mixture of monochlorin derivatives is then treated with a reagent capable of splitting off halogen hydrid, whereupon a mixture is

obtained which consists chiefly of trimethyl-ethylene

and the three other amylenes—

possibly in admixture with

The olefin mixture thus obtained is treated with hydrochloric acid, whereby, in the cold, only trimethyl-ethylene (formula VIII) adds on hydrochloric acid, being converted into 2-chlor-isopentane (formula I). The remaining mixture of the four other unsaturated hydrocarbons (formulæ IX, X, XI and XII) is isomerized, for instance, by the process described in the specification of Patent 1,102,655, whereupon trimethyl-ethylene is again formed and hydrochloric acid is added on to this and 2-chlor-isopentane again removed. If necessary, the hydrocarbon residue can be repeatedly subjected to the aforesaid operations. The total quantity of the olefins obtained from the original hydrocarbons is thus converted into pure 2-chlor-isopentane, which can further be converted into dichlor-isopentane and into isoprene.

The following example will serve to illustrate further the nature of my invention, which, however, is not confined to this example.

Example 1: Boil that fraction of a light petroleum which boils at temperatures up to about 40° or 45° C. in an enameled vessel provided with a fractionating column, and mix the vapors, after passing through the column, with chlorin, preferably in such a manner that the paraffin vapor is present in excess, and then subject the mixture to the action of light which is rich in chemically active rays, such for instance as sunlight, or subject them to the action of silent electric discharges, whereupon chlorination at once

takes place. The chlorination product and any unaltered hydrocarbon are then condensed and the liquid automatically led back into the boiling vessel, while the hydro-
5 chloric acid formed is led away in any suitable manner. The fractionating column is maintained at such a temperature that the chlorinated product is condensed and re-
10 turned to the vessel, while the unchlorinated product passes through and can be subjected to the action of chlorin. The product in the boiling vessel gradually grows richer in the chlorinated product and the boiling point of the liquid continually rises, and as soon as the
15 boiling point reaches between 75° and 80° C., the chlorination is stopped and the reaction product is subjected to fractional distillation. That part which boils at from 75° to 105° C. is vaporized and the vapor is passed over two
20 to three times its weight of powdered quick lime at from 375° to 450° C. The olefin produced is then stirred well for from 4 to 6 hours with three times its weight of concentrated aqueous hydrochloric acid, and any
25 unaltered olefin is thereupon distilled away from the tertiary isoamyl chlorid formed. The unaltered olefin is passed over calcined aluminium oxid at from 400° to 450° C. in order to isomerize it, and the reaction prod-
30 uct is again treated with concentrated aqueous hydrochloric acid in order to remove the trimethyl-ethylene which has been formed. These operations can be repeated as often as necessary.
35 In order to convert the tertiary isoamyl chlorid (formula I) into dichlor-isopentane, that portion of it boiling between 84° and 86° C., is boiled in an apparatus similar to that hereinbefore described and the vapors
40 are mixed with chlorin and subjected to the action of chemically active rays, such as sunlight or a uviol lamp, or to the action of a silent electric discharge. The dichlorid is obtained in almost quantitative yield and
45 consists chiefly of 2,3-dichlor-2-methylbutane of the formula

50 The same product (namely that of formula XIII) can also be obtained by gradually adding the theoretical quantity of sulfuryl

chlorid to pure trimethyl-ethylene, while continually shaking and cooling it so as to maintain a temperature of from -5° to 55 0° C.

To convert the said dichlorid into isoprene, it is passed slowly, at a pressure of about 20 millimeters, over heated contact material, such for instance as barium chlorid, at about 60 350° C. The hydrochloric acid is absorbed by milk of lime and the isoprene is condensed in any suitable manner, for instance by means of a carbon dioxid-toluene freezing mixture. 65

Now what I claim is:-

1. The process of producing 2-chlor-isopen-
tane by treating a mixture of petrol hydro-
carbons consisting chiefly of normal pentane
and isopentane with a chlorinating agent, 70
separating the monochlor derivatives, treat-
ing them with an agent adapted to split off
hydrochloric acid, acting on the mixture of
olefins obtained with hydrochloric acid, sep-
arating the 2-chlor-isopentane and acting on 75
the residue with an agent adapted to bring
about isomerization, and then acting on the
product with hydrochloric acid to obtain
more 2-chlor-isopentane.

2. The process of producing 2-chlor-isopen- 80
tane by treating a mixture of petrol hydro-
carbons consisting chiefly of normal pentane
and isopentane with a chlorinating agent, sep-
arating the monochlor derivatives, treat-
ing them with an agent adapted to split off hy- 85
drochloric acid, acting on the mixture of
olefins obtained with hydrochloric acid, sep-
arating the 2-chlor-isopentane and acting on
the residue with an agent adapted to bring
about isomerization, and then acting on the 90
product with hydrochloric acid to obtain
more 2-chlor-isopentane, again separating
the 2-chlor-isopentane and repeating the op-
erations of isomerizing, treating with hydro-
chloric acid and separating until substan- 95
tially the total quantity of olefins is trans-
formed into 2-chlor-isopentane.

In testimony whereof I have hereunto set
my hand in the presence of two subscribing
witnesses.

OTTO GRAUL.
